DEVICE FOR EXPANDING PISTONS

Gordon Blain Luse, Big Spring, Tex.

Application August 23, 1934, Serial No. 741,168

3 Claims. (Cl. 309—12)

My invention relates to improvements in devices for expanding pistons, and it consists in the combinations, constructions and arrangements herein described and claimed.

5 An object of the invention is to provide a means for expanding pistons so that old pistons can be used with rebored cylinders.

10 A further object of my invention is to provide a device for expanding pistons which is very simple, costs but little, but which holds the piston to a permanent size without undue expansion or contraction, as distinguished from those devices involving the use of springs.

15 A further object of the invention is to provide a device by means of which the expansion of the piston may be accurately gauged and in which the use of the simple means for expansion will permit of adjustment of the expansion, as desired.

20 A further object of the invention is to provide a device by means of which the piston skirt may be expanded uniformly from top to bottom.

25 A further object is to provide a means for expanding pistons which can be applied in a minimum of time.

Other objects and advantages will appear in the following specification and the novel features of the invention will be particularly pointed out in the appended claims.

30 My invention is illustrated in the accompanying drawing forming part of this application, in which:

Figure 1 is a side elevation of a piston showing means for expanding the same.

Figure 2 is a section on the line 2—2 of Fig. 1.

35 Figure 3 is a fragmentary view of the inner side of the piston wall showing the expanding means permanently in position, and,

Figure 4 is a perspective view of a pair of wedge members used for expanding the piston.

40 Referring particularly to Fig. 4, I have shown therein wedges, one of said wedges having a body portion 5 of maximum thickness at the end 6 and tapering to a minimum thickness at the edge 7. It is provided with a flange 8 having rivet openings 9. The depth of the wedge, that is to say, the distance from the outer edge 10 to the wall of the flange is substantially equal to the thickness of the piston wall.

45 A companion wedge 11 of the same depth is tapered in the opposite direction. The wedge is provided with a flange 12 having rivet holes 13. The length of the wedge 11 and of its flange 12 is greater than that of the companion wedge 5, this length being indicated by the distance from 55 the thinner end 14 to the point 15, the extra

length being indicated in Fig. 4 by dotted lines. The purpose of the extra length will be explained hereinafter.

In expanding a piston such as that shown at 16, in Fig. 1, a cut is made in the body portion thereof, this cut being indicated at 17 and extending from the lower edge 18, as viewed in Fig. 1, to the top of the skirt. This cut can be made by means of a hack saw in which two blades are placed side by side in the hack saw frame. 5

The wedge 5, the thickest part of which is less than the width of the cut, is now placed in the cut with the flange side of the wedge close to one edge of the cut, as shown in Fig. 1. Holes corresponding to the rivet holes 9 are bored in the piston and rivets 19 are passed through the flange 8 and are upset to securely hold the wedge 10 in position. Of course the outer wall of the piston is reamed to permit the upset portions of the rivet to be ground off smoothly with the outside of the 20 piston, as shown at 20 in Fig. 2.

The wedge 11 is now oiled and inserted at the lower end of the slot 17 as viewed in Fig. 1 and is pushed upwardly, the flange 12 being in contact with the inner piston wall. The wedges 5 25 and 11 are tapered at the same slant in opposite directions so that eventually as the wedge 11 is driven forwardly the piston will begin to expand. Accurate measurements can be taken of the expansion and the driving of the wedge 11 is discontinued when the proper expansion is secured. 30

Holes are now bored in the wall of the piston to correspond with the rivet holes 13. The wedge 11 is then removed and is cut off to correspond approximately with the wedge 5 in order to make a neat job. The wedge 11 is then replaced in the same manner and riveted by the use of rivets 19 which are countersunk at 20 as shown in connection with the wedge 5. 35

A piston expanded thus is practically as good as a new piston and acts in all respects like it. That is to say there is no undue expansion or contraction due to the expanding device. The piston is permanently expanded. 40

I am aware that piston expanders are not broadly new but those that I have seen involve more complicated mechanism or do not have the accuracy of adjustment or the ease of adjustment that is possible in the present construction. 45

I claim:

1. The combination with a piston having a longitudinal slot in the wall thereof, of a tapered wedge member disposed in the slot, said wedge member having one side abutting one edge of the 55

slot, a laterally extending flange integral with said wedge and secured to the inner face of the piston wall on one side of the slot, a second wedge member tapered in the opposite direction and slidable on said first named wedge member for expanding the piston to a predetermined amount, said second named wedge member having an integral flange, and means for securing said last named flange to the inner face of the piston wall 5 on the opposite side of the slot.

10 2. The combination with a piston having a longitudinal slot in the wall thereof, of a pair of oppositely tapered wedge members disposed in

the slot, each of said wedge members having integral flanges, means for securing one of said flanges to the inner wall of the piston on one side of the slot, and means for securing the other flange to the piston wall on the opposite side of the slot when the members have been adjusted to expand the piston the desired amount.

3. As an article of manufacture, a piston expanding member comprising a tapered body portion and an integral flange extending laterally 10 from said body portion and being provided with rivet openings.

GORDON BLAIN LUSE.
